UNITED STATES PATENT OFFICE.

CHARLES F. CHOUFFET AND EDWARD J. ISLEY, OF BUFFALO, NEW YORK.

DESIGN FOR A CLOCK-FRAME.

SPECIFICATION forming part of Design No. 31,920, dated December 5, 1899.

Application filed July 15, 1899. Serial No. 724,002. Term of patent 3½ years.

To all whom it may concern:

Be it known that we, CHARLES F. CHOUFFET and EDWARD J. ISLEY, citizens of the United States, residing in Buffalo, in the county of Erie and State of New York, have invented and produced a new and original Design for a Clock-Frame, of which the following is a specification, reference being had to the accompanying drawings, forming part thereof.

In the drawings, Figure 1 is a face view of a clock-frame arranged according to our design, and Fig. 2 is an edge view of the same.

As seen in the drawings, the profile 1 of the clock-frame, taken in face view, resembles that of a dust-pan having a recess or casing 2 formed in its center. As seen in Fig. 2 this casing 2 extends rearwardly sufficient to form a base to the clock-frame and when in position rests upon the lower edge of the face-plate 1 and lower rear edge of the recessed

casing 2. The space between the recess 2 and the edge of the face-plate 1 affords space for any suitable words or dates.

The design consists in a clock-frame the face-plate of which resembles a dust-pan and the casing of which is centrally formed in said face-plate.

Having thus described our invention, what we claim, and desire to secure by Letters Patent, is—

The design for a clock-frame as herein shown and described.

In testimony whereof we have signed our names to this application in the presence of two subscribing witnesses.

CHARLES F. CHOUFFET.
EDWARD J. ISLEY.
